OPERATING MECHANISM

Filed Jan. 24, 1928

UNITED STATES PATENT OFFICE

HOWARD E. GINTHER, OF LA PORTE, INDIANA, ASSIGNOR TO BASTIAN-MORLEY CO., OF LA PORTE, INDIANA, A CORPORATION OF INDIANA

OPERATING MECHANISM

Application filed January 24, 1928. Serial No. 249,092.

This invention relates to an improved thermostatically controlled mechanism for operating and controlling a valve.

One object of the invention is to construct 5 an improved mechanism of this character having multiplying levers which are relatively simple in construction and which are arranged and related to swing freely to actuate or control the valve element at all times. 10 Another object of the invention is to construct a valve operating mechanism having parts which may be economically manufactured and readily assembled.

Another object of the invention is to construct 15 an improved mechanism of this character in which the supporting pivots for its levers are disposed out of the path of the combustible medium passing through the casing enclosing such mechanism, so that the heavier 20 ingredients and foreign matter in the combustible medium cannot collect on the pivots and affect the free swinging of the levers.

A further object of the invention is to provide 25 an improved mechanism of this character comprising a minimum number of parts so arranged and constructed that the casing therefor may be relatively small and shaped 30 to permit unobstructed flow of the combustible medium through it, thus avoiding the danger of foreign matter and heavy ingredients in the combustible medium accumulating in the casing.

Other objects of the invention will be apparent 35 to those skilled in the art to which my invention relates from the following description taken in connection with the accompanying drawings, wherein

Fig. 1 is a view, partly in elevation and partly in section showing a water heater of 40 the storage type having a burner and a thermostatically controlled mechanism embodying my invention for operating the valve in the supply pipe connected to the burner.

Fig. 2 is a longitudinal section through the 45 casing for the valve operating mechanism showing the latter, the valve and the thermostat elements; the valve element being seated.

Fig. 3 is a fragmentary view of the parts 50 shown in Fig. 2, but showing the valve element unseated.

Fig. 4 is a fragmentary elevation of the casing.

Fig. 5 is a section on the line 5—5 of Fig. 2.

Fig. 6 is a section on the line 6—6 of Fig. 2.

In the drawing, 1, 2, indicate suitable thermostatic elements surrounded by the medium to be heated, such medium in the present application of my invention being water. The thermostat elements 1, 2, are, for illustrative purposes, shown projecting into a suitable tank 3, into which leads a supply pipe 4 connected to a suitable source of supply, the tank serving as a reservoir for the heated water and having an outlet pipe 5 leading from its upper portion to one or more points for use. 55

In the form of tank 3 illustrated, its side wall 3^a is extended downwardly to form a skirt below the bottom 3^b of the tank, the skirt forming a fire box 6 and the bottom 3^b is formed (a) centrally with an opening 7 having a ring therein forming a mounting for the neck portion of a spreader 8 and (b) eccentrically with an opening for the lower open end of a flue 9 leading through the tank 3 and its top wall to carry off the products of combustion. 10 indicates a suitable drain pipe, preferably leading from the lower portion of the spreader 8, its outer portion carrying a valve 10^a. The spreader is provided with a deflecting wall 8^a which directs the 70 water into a riser tube 8^b leading to the upper portion of the tank. 11 indicates a suitable burner, preferably adapted for burning natural or artificial gas, the gas being supplied by a pipe 12. 75

13 indicates a casing enclosing a valve 14 and an operating mechanism, indicated as an entirety at 15: the casing is interposed in the pipe 12, so that the combustible medium flows through the casing, such flow being controlled by the valve 14. The casing 13 comprises a main member 13^a and a removable member to which reference will later be made. The main member 13^a is shaped to form a chamber 13^a for the valve element 14^a and a chamber 13^b for the operating mechanism 15, these chambers being separated by an internal flange or rim 13^c the opening through which forms the valve opening and the circumferential edge thereof—preferably the 80 85 90 95 100

upper edge—being shaped form a true circle to constitute the valve seat for the valve element 14^a. The valve element preferably comprises a relatively heavy ball (for example, a steel ball) and is impelled toward its seat by gravity and the pressure of the gas supplied by the pipe 12. The annular rim 13^c serves to collect foreign matter and heavier ingredients in the gas. The side wall of the chamber 13^a is preferably of annular shape and is restricted in its diameter so that the ball cannot become so dislocated from its seat that it will not gravitate onto its seat when the casing is positioned as shown in the drawings and the parts of the operating mechanism 15 are in normal position. At one side the side wall of the chamber 13^a is formed with a collar which forms a suitable connection for the end of the supply pipe 12; and its top wall is formed with an opening 16, which is closed by a removable plug 17. The side walls of the chamber 13^b are vertical and have planular inner surfaces and their inner faces are spaced apart a distance substantially equal to the external diameter of the supply pipe section 12^a leading from the casing 13^x to the burner 11; accordingly, the casing is not only of minimum width to reduce its size and amount of metal required for its walls, but such construction eliminates unnecessary interior ledges or other portions that would affect the free flow of the gas or form collecting walls for ingredients and foreign matter contained in it. The lower portion of the casing is shaped to form a depending collar to which the pipe section 12^a is suitably connected. At one end the casing 13 is provided with a hollow boss 18 exteriorly threaded to removably fit a suitable ring mounted in the wall of the tank 3. The thermo-element 1 (which preferably consists of copper or other metal having a relatively high coefficient of expansion) comprises a tube mounted at its outer end in a liquid tight manner in the boss 18, whereas the thermo-element 2 (which preferably consists of invar metal or other material having a relatively low coefficient of expansion) comprises a rod and extends through the tube 1, its outer end operatively engaging the operating mechanism 15 in the manner to be later set forth. The inner end of the tube 1 is sealed by a hollow plug 19. The inner wall of the plug is threaded and the inner end of the rod 2 is threaded therein, such connection serving to adjustably connect the elements together, for which purpose the inner end of the rod 2 may be formed with a kerf (not shown).

20 indicates an opening formed in that end wall of the casing opposite to the boss 18. The opening 20 is closed by the removable casing member (already referred to) which comprises a cap or hood 21, arranged to co-operate with the walls of the casing member

13^x to support the operating mechanism 15. The cap 21 is provided with a flange 21^a which is removably secured to the end wall of the casing 13^x in a liquid tight manner, for which purpose a gasket (not shown) may be used. The cap 21 may be formed from sheet metal. 70

The operating mechanism 15 comprises a main lever 23 pivoted at its upper portion on a transverse shaft or pin 24, which is mounted at its opposite ends in the side walls of the casing, a second lever 25 pivotally connected at its upper end to the lower portion of the main lever 23, by a pivot 23^a and operatively connected at its lower end to the casing 13 (preferably an adjustable abutment 26); a third or intermediate lever 27 pivotally mounted on a transverse shaft 28 mounted at its opposite ends in the side walls of the cap 21 and pivotally connected to the main lever 23 by a pivot 28^a and a combined thrust and snap action means 29 which actuates the valve element 14^a to control its unseating and seating. The abutment 26 preferably consists of a rod threaded at its outer portion in an opening 26^a formed in the front end wall of the casing 13^x and extends through the opening, whereby its outer end may be engaged by a suitable tool. The main lever 23 is stamped or otherwise formed from a sheet metal blank having portions 23^a folded on a median line into face to face relation and legs 23^b which have off-sets 23^c to dispose their outer portions in parallel relation upon opposite sides of the intermediate lever 27. This form of construction has several advantages, which permit the lever to be made from relatively thin sheet metal without sacrificing its strength; namely the fold along the bottom reinforces the folded portions longitudinally, it provides two thicknesses of metal substantially in line with the direction of thrust incident to the movement of the thermo-rod 2 and it transmits this thrust to the opposite sides of the pivot 28^a, which in turn swings the intermediate lever 27 without tendency to distort the shaft or pin 28 for the latter. By insuring a free swinging of the lever 27, the combined thrust and snap acting means 29 actuate and control the valve 14 in a positive manner due to slight changes in temperature of the water in the tank 3. The legs 23^b are formed with elongated slots 23^d for the pin 28 to permit operation of the levers 23 and 27 to the position shown in Fig. 3. The second lever 25 is also preferably formed from sheet metal bent or otherwise shaped to form relatively wide thrust walls 25^a, 25^b for the rods 2 and 26, respectively, which walls are reinforced along their vertical sides by flanges 25^b, the upper ends of which serve as bifurcations to straddle the lever 23 and the lower ends of which straddle the free end of the adjusting rod 26 so that the latter maintains the levers in position and against dislocation once the parts are as- 125

sembled. As shown, the wall 25^a is curved on transverse lines, such curvature serving to prevent the rod 2 from dropping down and engaging the inner wall of the tube 1.

5 The rod 2 may be arranged to engage either lever 23 or 25, since they are pivoted together at a point intermediate their operative connections with the casing 13, but in the preferred construction, the rod 2 engages the lever 25, as above set forth.

10 The pivot or supporting shaft 24 may comprise two parts 24^a, 24^b, to facilitate the mounting of the lever 23 in the casing 13. Each part has a threaded portion removably fitting a threaded opening in one side wall of the casing. The part 24^b is formed with an axial opening 24^a leading inwardly from its inner end and the part 24^a is reduced at its inner end, such reduced portion extending through aligned openings formed in the folded portions 23^a of the lever 23 and into the opening 24^a (see Fig. 6); the inner end of the part 24^b engaging one side face of the lever 23 and the shoulder formed by the reduced portion of the part 24^a engaging the other side face of the lever to position it centrally of the casing.

15 Of the combined thrust and snap action means 29, 30 indicates a plunger or thrust member pivotally connected at its lower end to the inner end of the lever 27 so as to be actuated thereby to lift or unseat the valve element 14^a or permit the seating thereof when the lever 27 is operated in a manner to be later described. The free end of the lever 27 is preferably bifurcated, as shown in Fig. 6 and the lower end of the plunger 30 is reduced to fit between these bifurcations. The plunger or thrust member 30 extends upwardly and is arranged to move in an endwise direction substantially axially of the valve seat as it operates upwardly and downwardly.

20 With the parts constructed and arranged as described, operation of the element 2 toward the right due to fall or drop in temperature of the water in the tank 3, will swing the adjacent ends of the levers 23 and 27 upwardly and the latter will move the plunger substantially endwise upwardly; when the element 2 moves toward the left, due to rise in temperature of the water in the tank 3, these parts will move in the opposite direction. 31 indicates a spring carried by the upper end of the plunger 30 and interposed between the plunger and valve element 14^a, being connected to and supported by the plunger 30 so as to move upwardly and downwardly therewith. The spring 31 preferably consists of a coiled section of wire, the coil being of conical shape to form at its upper end a pocket which supports the valve element 14^a when it is unseated. The upper end of the spring 31 is of a size to fit within the valve seat and to engage the valve ele-

ment at points substantially concentric to the axis of the valve seat.

25 The valve element 14^a is held to its seat by its weight and also by the pressure of the fuel flowing in the pipe 12. As the thrust member 30 moves upwardly, it compresses the spring 31 against the combined resistance of the weight of the valve element and pressure of the fuel until the tension of the spring overcomes such resistance, whereupon the 70 spring 31 with a relatively quick action, will unseat the valve element and allow a full supply of the fuel to pass the valve to the burner. This operation will insure proper and immediate ignition of the burner from 75 its pilot 11' and also prevent waste of fuel.

80 In the movement of the plunger or thrust member 30 downwardly, the tension of the spring 31 will hold or support the valve element until its weight supplemented by the 85 gas pressure overcomes the spring tension, whereupon the valve element will engage its seat with a snap action.

85 The spring 31 is preferably connected to the thrust member 30 in a detachable manner. For this purpose, the upper end of the thrust member is formed with a screw threaded opening to receive a screw 32. The head of the screw is provided with a collar 33, which co-operates with a washer 34 held on the upper end of the thrust member 30 by the head of the screw to detachably engage the lower end convolution of the spring 31 and thus secure it in position. The head of the screw 32 may be provided with a slot to receive a 90 tool whereby it may be readily operated to clamp the spring 31 in position or release it.

95 The abutment 26 is adjustable to different positions so that the temperature of the water in the tank 1 can be kept at any desired temperature within certain limits. In other words, by moving the inner end of the abutment 26 toward or from the lever 25, the latter may be caused to engage the abutment at any desired time in the movement of the levers 23, 25, and thus regulate the opening and closing of the valve 14.

100 It will be noted that in my construction I associate with the opening 20, through which the levers 23 and 25 and the combined thrust and snap action means 29 are inserted when assembly is being made, a cap or hood 21; also, that the lever 27 and outer portion or long arm of the lever 23 extend through this opening into the cap 21, that the shaft 28 for the lever 27 is mounted in the side walls thereof, and that the pivot connection between the levers 23 and 27 are within the cap 21. As the pivot 24 for the lever 23 and the pivot between the levers 23 and 25 are disposed at the inner end of the chamber 13', it will be seen that all of the pivots for these parts are disposed out of the path of flow of the fuel. Further advantages incident to this form of construction are that it permits the casing to 110

be relatively small; the pivots for the levers 23, 27, are widely separated so that their swinging portions may be made relatively long to insure the desired leverage; the levers 5 23 and 27 are so related that the pivot connection between them can be readily changed without affecting their lengths or any of the other parts of the mechanism; and greater access to the levers results.

10 To those skilled in the art to which my invention relates many changes in construction and widely differing embodiments and applications of the invention will suggest themselves without departing from the spirit and 15 scope thereof. The descriptions and disclosures herein are purely illustrative and are not intended to be in any sense limiting.

What I claim is:

1. In mechanism of the class described, the 20 combination with a casing having inlet and outlet connections for fuel and a valve in said casing, of a pair of levers normally disposed in the same plane and pivotally mounted at their outer ends in said casing and 25 pivotally connected together at their inner portions, means carried by one of said levers for actuating the valve element of said valve, a second lever operatively connected to the other lever and said casing, and means 30 engaging said second lever and operating through it and said pair of levers to operate said valve element actuating means.

2. In mechanism of the class described, the 35 combination with a casing having inlet and outlet connections for fuel and a valve in said casing, of a pair of levers pivotally connected together at their inner portions and pivotally mounted at their outer ends in said casing, the pivot mountings being disposed 40 out of the path of flow of the fuel through said casing, means carried by one of said levers for actuating the valve element of said valve, a second lever operatively connected to the other lever and said casing, and means 45 engaging said second lever and operating through it and said pair of levers to operate said valve element actuating means.

3. In mechanism of the class described, 50 the combination of a casing having inlet and outlet connections for fuel and shaped to form chambers at opposite sides of the path of flow of the fuel through the casing, a valve in said casing, a pair of levers pivotally connected together at their inner portions, the outer portions of said levers extending in opposite directions into the outer portions of said chambers, pivots for the outer ends of said levers supported by the 55 walls of said chambers, whereby said pivots are disposed out of the path of flow of the fuel through said casing, means carried by one of said levers for actuating the valve element of said valve, a second lever operatively 60 connected to the other lever and said 65

casing, and means engaging said second lever and operating through it and said pair of levers to operate said valve element actuating means.

4. In mechanism of the class described, the 70 combination of a casing having inlet and outlet connections for fuel and comprising a main member and a removable member, a valve in said casing, a pair of levers pivotally connected together at their inner portions and pivotally mounted at their outer ends in said main member and said removable member, respectively, means carried by one of said levers for actuating the valve element of said valve, a second lever operatively connected to the other lever and said casing, and means 75 engaging said second lever and operating through it and said pair of levers to operate said valve element actuating means.

5. In mechanism of the class described, the 80 combination of a casing having inlet and outlet connections for fuel and comprising a main member and a removable member, a valve in said casing, a pair of levers pivotally connected together at their inner portions and pivotally mounted at their outer ends in said main member and said removable member, respectively, the pivot 85 mountings for the outer ends of said levers being disposed out of the path of flow of the fuel, means carried by one of said levers for actuating the valve element of said valve, a second lever operatively connected to the other lever and said casing, and means 90 engaging said second lever and operating through it and said pair of levers to operate said valve element actuating means.

6. In mechanism of the class described, the 95 combination of a casing comprising a main member and a removable member, an inlet and an outlet for fuel at one end of said main member, a valve in said casing between the inlet and outlet, the end wall of said casing adjacent said valve being formed with an opening which is closed by said removable member, a pair of levers having portions extending through said opening, pivotal connections between said levers, the outer end of one lever being mounted on a pivot supported in said main casing member adjacent the end thereof remote from said opening and the outer end of the other lever being mounted on a pivot supported in said removable casing member, means carried by the last mentioned lever for actuating the valve element of said valve, and means for swinging the 110 first mentioned lever.

7. In mechanism of the class described, the 115 combination of a casing comprising a main member and a removable member, an inlet and an outlet for fuel at one end of said main member, a valve in said casing between the inlet and outlet, the side walls of the casing 120 between said valve and said outlet being 125

engage said abutment, the thrust wall engaged by said thermostatic element being shaped to support the engaging end thereof.

14. In mechanism of the class described, the combination with a casing, a valve therein and thermostat elements associated with said casing, the movable one thereof extending into said casing, of a set of multiplying levers between the movable thermostat element and the valve element of said valve, and an abutment in said casing, said levers comprising a main lever pivotally mounted in said casing, a second lever pivotally connected to said main lever and engaging said abutment, an intermediate lever pivotally mounted in said casing and pivotally connected to said main lever and means carried by the intermediate lever for actuating the valve element of said valve, said second lever having thrust walls one to be engaged by the movable thermostat element and the other to engage said abutment, and side walls disposed at the opposite sides of said abutment whereby the latter maintains said levers in operative relation.

15. In mechanism of the class described, the combination with a casing having an inlet and an outlet for fuel, a valve in said casing, and thermostat elements associated with said casing, one thereof being movable and extending into said casing, of levers operatively engaging said casing at points at opposite sides of said movable thermostat element and pivotally connected together, a portion of one of said levers being disposed in line with the movable thermostat element, whereby the movement of said element will operate said levers one of said levers having a long arm terminating in spaced legs, a separate lever pivotally mounted at its outer end in said casing and having its inner portion disposed between said legs, pivot connections between said legs and the inner portion of said separate lever, and means carried by the inner end of said separate lever for actuating the valve element of said valve.

16. In mechanism of the class described, the combination with a casing having an inlet and an outlet for fuel, a valve in said casing and thermostat elements associated with said casing, one thereof being movable and extending into said casing, of levers operatively engaging said casing at points at opposite sides of said movable thermostat element and pivotally connected together, a portion of one of said levers being disposed in line with the movable thermostat element, whereby the movement of said element will operate said levers, one of said levers having a long arm terminating in spaced legs, a separate lever pivotally mounted at its outer end in said casing and having its inner portion disposed between said legs, pivot connections between said legs and the inner portion of said separate lever, and means carried

by the inner end of said separate lever for actuating the valve element of said valve, said means comprising a plunger and a compression spring co-acting with the valve element due to its weight and pressure of fuel supplied through said inlet to unseat and seat said valve with a snap action. 70

17. In mechanism of the class described, the combination with a casing having an inlet and an outlet for fuel, a valve in said casing and thermostat elements associated with said casing, one thereof being movable and extending into said casing, of levers operatively engaging said casing at points at opposite sides of said movable thermostat element and pivotally connected together, a portion of one of said levers being disposed in line with the movable thermostat element, whereby the movement of said element will operate said levers, one of said levers having a long arm terminating in spaced legs, a separate lever pivotally mounted at its outer end in said casing and having its inner portion disposed between said legs, pivot connections between said legs and the inner portion of 80 said separate lever, and means carried by the inner end of said separate lever for actuating the valve element of said valve, said means comprising a plunger and a compression spring co-acting with the valve element due 90 to its weight and pressure of fuel supplied through said inlet to unseat and seat said valve with a snap action, and said valve element acting through said spring to maintain the latter and said plunger in position to move 95 upwardly and downwardly as said separate lever is operated. 100

In testimony whereof, I have hereunto subscribed my name.
